UNITED STATES PATENT OFFICE

BURNELL MALCOLM CALVERT, OF TERRE HAUTE, INDIANA

DESIGN FOR AN AUTOMOBILE DOOR

Application filed January 22, 1932. Serial No. 42,595. Term of patent 3½ years.

To all whom it may concern:

Be it known that I, BURNELL MALCOLM CALVERT, a citizen of the United States, residing at Terre Haute, in the county of Vigo and State of Indiana, have invented a new, original, and ornamental Design for an Automobile Door, of which the following is a specification, reference being had to the accompanying drawing, forming part thereof.

Figure 1 is a side elevational view of an automobile door showing my new design; and Fig. 2 is a perspective view to a somewhat enlarged scale.

I claim:

The ornamental design for an automobile door as shown.

BURNELL MALCOLM CALVERT.
